TOOL HANDLE STRUCTURE

Wallace I. Lindgren, 3723 Dartmouth Drive,
Minnetonka, Minn. 55345

Filed Dec. 28, 1970, Ser. No. 26,673

Term of patent 14 years

Int. Cl. D8—05

U.S. Cl. D8—83

FIG. 1 is a view in perspective of a tool handle structure showing my new design;

FIG. 2 is a view thereof in elevation of one side with the other side being the same;

FIG. 3 is a view thereof in end elevation;

FIG. 4 is a view thereof in top plan; and

FIG. 5 is a view thereof in bottom plan.

The broken line disclosure of a screwdriver blade is shown for illustrative purposes only.

I claim:

The ornamental design for a tool handle structure, as shown and described.
